UNITED STATES PATENT OFFICE.

FRANK S. GUILD, OF MERCHANTVILLE, NEW JERSEY, ASSIGNOR TO THE CURTIS PUBLISHING COMPANY, OF PHILADELPHIA, PENNSYLVANIA, A CORPORATION OF PENNSYLVANIA.

DESIGN FOR A FONT OF TYPE.

44,101.

Specification for Design.

Patented May 27, 1913.

Application filed March 30, 1912. Serial No. 687,531. Term of patent 14 years.

To all whom it may concern:

Be it known that I, FRANK S. GUILD, a citizen of the United States, residing at Merchantville, in the county of Camden and State of New Jersey, have invented a new, original, and ornamental Design for a Font of Type, of which the following is a specification.

The accompanying drawing, which is made a part hereof and to which reference is made, shows the form and design of the face of each letter and character composing said font of type, as well as the ornamental character of the font as a whole.

What I claim is:

The design for a font of type shown in the accompanying drawing.

In witness whereof, I have hereunto set my hand and seal at Philadelphia, Pennsylvania this 18th day of March, A. D. nineteen hundred and twelve.

FRANK S. GUILD. [L. S.]
